DESIGN FOR AN AUTOMOBILE LICENSE PLATE ORNAMENT

James V. West, Arlington, Va.

Application September 10, 1940, Serial No. 94,915

Term of patent 7 years

To all whom it may concern:

Be it known that I, James V. West, a citizen of the United States, residing at Arlington, in the county of Arlington and State of Virginia, have invented a new, original, and ornamental Design for an Automobile License Plate Ornament, of which the following is a specification, reference being had to the accompanying drawing, forming part thereof.

The single figure in the drawing is a front ele-

vational view of an automobile license plate ornament, showing my new design.

The automobile license plate ornament of my design is substantially thin and flat, and the rear portion is plain. The drawing is shaded to show contrasting appearance.

I claim:

The ornamental design for an automobile license plate ornament, as shown and described.

JAMES V. WEST.
